(57) **CLAIM**

The ornamental design for an electronic device wrist mount, as shown and described.

DESCRIPTION

FIG. 1 is a front, top and left side perspective view of an electronic device wrist mount showing our new design; FIG. 2 is a rear, bottom and right side perspective view thereof;

FIG. 3 is a front, top and right side perspective view thereof; FIG. 4 is a rear, bottom and left side perspective view thereof;

FIG. 5 is a left side elevational view thereof;

FIG. 6 is a right side elevational view thereof;

FIG. 7 is a rear elevational view thereof;

FIG. 8 is a front elevational view thereof;

FIG. 9 is a top plan view thereof;

FIG. 10 is a bottom plan view thereof; and,

FIG. 11 is a front cross-sectional view thereof taken along the lines 11-11 from FIG. 9.

The broken lines in the drawings are included for the purpose of illustrating environmental structure and form no part of the claimed design.

1 Claim, 11 Drawing Sheets
